UNITED STATES PATENT OFFICE.

DAVID L. GRAFF, OF NEW YORK, N. Y., ASSIGNOR TO NATIONAL CARBON COMPANY, INC., A CORPORATION OF NEW YORK.

PORTABLE ELECTRIC LIGHT.

1,373,611.

Specification of Letters Patent.

Patented Apr. 5, 1921.

Application filed April 25, 1918. Serial No. 280,649.

To all whom it may concern:

Be it known that I, DAVID L. GRAFF, a citizen of the United States, and a resident of New York, in the county of New York and State of New York, have invented certain new and useful Improvements in Portable Electric Lights, of which the following is a specification.

The invention relates to improvements in portable electric lights, and it consists in the novel features, arrangements, construction and combinations of parts hereinafter described, and particularly pointed out in the claims.

15 My invention has reference more particularly to a small portable electric light which may be used in various connections, as in the hand, or by being hung upon a support, or by being connected with a belt extended 20 around the waist of the user, or by being suspended from a button on the coat or other garment of the user, and otherwise, and my said flash light comprises a suitable casing preferably having inclosing flaps and 25 containing parallel battery cells, suitable circuit making and breaking means, means for spacing said cells apart, and a suitable electric light bulb, with a reflector and lens adapted to project a light from the side of 30 said casing, the reflector and lamp socket extending into the space between the battery cells.

The invention involves a number of novel 35 details and features of construction and arrangement and also several modifications of construction, all of which may be better understood from the detailed description hereinafter presented, with reference to the accompanying drawings, in which:

40 Figure 1 is a perspective view of a portable electric light constructed in accordance with and embodying my invention;

Fig. 2 is a rear elevation of the same, on a larger scale, the upwardly extending handle or loop shown in Fig. 1, being in Fig. 2 45 illustrated in its collapsed or folded and locked position;

Fig. 3 is a vertical section, partly broken away and on a larger scale, through the 50 same, taken on the dotted line 3—3 of Fig. 2;

Fig. 4 is a rear face view of the same, with the inclosing flaps of the exterior casing opened outwardly to expose the battery

cells and internal features of the electric 55 light, the said cells being shown in operative position;

Fig. 5 is a similar view of the same, with the batteries omitted, and a connecting bar secured to the top and bottom of the exterior casing centrally between the batteries also being omitted;

Fig. 6 is a horizontal section through the portable electric light of my invention, taken on the dotted line 6—6 of Fig. 3, and 65 showing the device as having been turned over through a quarter circle from its position shown in Fig. 1, whereby the circuit making and breaking switch is caused to appear at the then upper end or top of the 70 light;

Fig. 7 is a vertical section through the casing, taken about on the dotted line 7—7 of Fig. 6;

Fig. 8 is a perspective view, illustrating 75 partly in full lines and partly in dotted lines, some of the circuit connections of the electric light shown in Figs. 1 to 7 inclusive;

Fig. 9 is a section corresponding substantially with Fig. 7, but illustrating a modified arrangement of the circuit connections;

Fig. 10 is a similar section showing another modified arrangement of the circuit 80 connections;

Fig. 11 is a view substantially corresponding with Figs. 7, 9 and 10, but illustrating a further modified construction of my invention, the exterior casing in this instance being of tin or other metal, in lieu of the 90 non-conducting material used for the casing in the previous illustrations presented in the drawings;

Fig. 12 is a section through the same, taken on the dotted line 12—12 of Fig. 11; 95

Fig. 13 is a further section through the same, taken on the dotted line 13—13 of Fig. 11;

Fig. 14 is a perspective view showing the interior of the casing illustrated in Figs. 1 100 to 10 inclusive, which casing is in the completed article covered with leather or other suitable material;

Fig. 15 is a detached perspective view of a metal bar for connecting the top and bottom of the exterior casing and located between the cells, as shown in Fig. 4, for preventing, as one function, the separation of

said top and bottom in a direction from each other which might tend to interfere with the circuit;

Fig. 16 is a diagrammatic view indicating 5 the circuit for the construction shown in Figs. 1 to 8 inclusive and Figs. 11, 12 and 13;

Fig. 17 is a diagrammatic view illustrating 10 the circuit for the construction shown in Fig. 9, and

Fig. 18 is a diagrammatic view indicating 15 the circuit for the construction shown in Fig. 10.

In the drawings, referring more particularly 20 to the embodiment of my invention illustrated in Figs. 1 to 8 inclusive, 14, 15 and 16, 20 designates the shell or casing of the flash light, and this casing, as shown in Fig. 14, is of approximately oval shape and 25 is open at one side, said casing comprising a body portion 21 having an opening 22 therein and top and bottom sections 23, 24. The body portion 21 forms the face and 30 ends of the casing, and said casing may be made of any suitable material such as wood, fiber, metal or the like. When the casing is employed horizontally or as shown in 35 Figs. 4, 5, 14, the body portion 21 will stand vertically and the parts 23, 24 will constitute the top and bottom of the casing, but when the casing is employed vertically, as 40 shown in Figs. 1 and 2, the parts 23, 24 will represent the ends of the casing, and the end portions of the body 21 will represent the 45 top and bottom of the casing. We may refer to the parts 23, 24 as constituting the top and bottom of the casing, since the flash light employing the same may be disposed horizontally or vertically, as occasion may 50 require. The casing of the outline shown in Fig. 14, whether made of the materials mentioned or a combination thereof, is highly desirable in carrying out my invention, since the flash light made therefrom is of 55 convenient shape and may readily be equipped with features rendering the flash light convenient of use. The casing 20 has an open back, as shown in Fig. 14, and will be covered with suitable material, especially 60 at its front and ends, as canvas, leather or the like. The covering applied to the body 21 is numbered 25, and this covering may be fastened to said body by any suitable means, and is formed with two flaps 26, 27, 65 respectively, provided with snap fasteners 28 and adapted to be closed over the open back of the casing and secured together by the aforesaid fasteners 28. The flaps 26, 27 are of sufficient length to overlap each 70 other at their adjoining portions, as shown in Fig. 2, and not only close the back of the casing, but present a neat appearance and a closure which may be readily opened when it is required to introduce new battery cells 75 within the casing. The flaps 26, 27 have

straps 29 secured thereto at their ends, and these straps will be equipped with button-holes 30, or other convenient means, whereby the flashlight may be suspended from a button or buttons on a coat or other garment. 70 The straps 29 also serve the further important convenience of permitting a belt to be strung through them, whereby the flash light may be carried from a belt, leaving the hands free. I also equip the flash light at 75 one end of the body portion 21 with a strap 31 which is fastened at its ends to the body of the flash light and when opened outwardly constitutes an open loop, as shown in Fig. 1. The strap 31 permits of the 80 flash light being suspended on a hook or other means of support, and said strap is preferably formed at its center with a button-hole 32 which permits the flash light to be suspended from a button on a coat or 85 other garment. It is desirable that the strap 31 should be capable of being folded down against the flash light and secured in its folded position, so that when the strap is not in use it may be kept out of the way, 90 and this folded position of the strap 31 is illustrated in Fig. 2 in which it may be seen that the parts of the strap 31 are secured in folded position by means of the two members 33, 34 of a snap fastener. 95

Within the casing of the flash light is provided a block 35 preferably of wood or other non-conducting substance, this block being arranged centrally between the top and bottom of the casing and affording in 100 conjunction with the ends of the body portion 21 two cradles or chambers adapted to receive the battery cells 36, 37, as illustrated in Figs. 3 and 4. The cells 36, 37 are omitted from Fig. 5. The block of wood 105 35 has secured upon its face a threaded sleeve 38, and this sleeve projects through the opening 22 in the front of the casing, said opening 22 being substantially at the center of said front. The 110 upper end of a conductive strip 39 is electrically connected to a base flange formed on the sleeve 38. The front portion of the block 35 contains a tapered chamber 40, and back of this chamber 40 and communicating 115 therewith is a hole 41 leading rearwardly to a vertical groove 42 formed in the back of the block 35. Within the groove 42 is secured a conductor strip 43 which crosses the hole 41 and is bent inwardly at its middle portion, as at 44, to afford a contact for one terminal of the electric lamp 45, which is of the usual miniature type and is screwed within a lamp socket carried by and shown as formed in one piece with a metallic reflector 46 and in electrical connection therewith. The lamp 45 and reflector 46 are inserted within the sleeve 38 and entered within the recess or chamber 40 formed in the block 35, as shown in Fig. 3, the end termi- 120 125 130

nal of the lamp being against the inwardly bent portion 44 of the conducting strip 43. The lamp 45 and reflector 46, together with a customary lens 47, are secured in operative 5 position by means of an external threaded sleeve or lens-ring 48 screwed upon the sleeve 38 and having a flange which engages said lens and presses the same against the outer flanged edge of the reflector 46, as 10 illustrated in Fig. 3.

The block 35 is concaved at opposite edges to engage and bear against the battery cells 36, 37, as shown in Fig. 3, and the 15 end portions of the body 21 of the casing 20 are outwardly concaved to receive said cells; and the flaps 26, 27 of the exterior covering, being flexible, are adapted to lie 20 against the rear surfaces of said cells, as shown in Fig. 3, and retain the same in position between the top and bottom of the main casing.

The conducting strip 43 secured within the groove 42 of the block 35 is in electrical connection at its lower end with a spring 25 contact 49, which is a strip of metal extending from the conductor 43 and below the block 35 and then normally flexed upwardly, as shown in Fig. 5, so as to make a firm electrical engagement with the zinc 30 or negative pole of the battery cell 36, as shown in Fig. 4. Below the block 35 is a spring contact strip 50 which extends laterally from below said block and is flexed upwardly, as shown in Fig. 5, so as to make 35 a firm electrical contact with the carbon or positive pole of the battery cell 37, as shown in Fig. 4, and the strip 50 is electrically continuous upwardly along the front of the block 35, with the strip 39, and the upper 40 end of which is in engagement with the base-flange of the threaded sleeve 38, an electrical connection between the positive pole of the battery cell 37, sleeve 38, sleeve 48, reflector 46 and the side of the lamp 45 being thus effected, and since the strip 45, through the spring contact 49, is in engagement with the negative pole of the battery 36, an electrical connection between said pole of said battery and the end terminal of the lamp is formed. To complete 50 the circuit, however, there must be a connection between the negative pole of the battery 37 and positive pole of the battery 36, and to accomplish this result I provide 55 at the inner side of the top 23 of the casing two conducting strips 51 52 and a circuit making switch or slide 53, the latter being within a housing 54 secured to the top 23 of the casing 20 by suitable eyelets, 60 one of which, 55, is in electrical connection with the strip 51. The circuit making and breaking switch 53 is of customary type and it is in electrical connection with the housing 54 and may be slid into electrical connection 65 with an eyelet 56 (Fig. 7) secur-

ing one end of the contact strip 52 to the top of the casing 20. When the switch 53 is in the position shown in Fig. 7, there is no circuit through the lamp, and hence the light has not been lighted, but when the 70 switch 53 is moved to engage the eyelet 56, the circuit will be completed and the lamp lighted, the circuit then being from the switch 53 through the housing 54, eyelet 55, and strip 51 to the positive pole of the 75 battery cell 36, thence through said cell and the contact 49 and conductor 43 to one terminal of the lamp, and through the lamp, reflector 46, sleeve 38 and conductors 39, 50 to the positive pole of the battery 37, 80 and thence through the cell 37, contact strip 52 and eyelet 56 to the switch 53. The sliding of the switch 53 from the eyelet 56 will break the circuit and extinguish the light. The circuit is illustrated 85 grammatically in Fig. 16.

The switch 53 is of known type and I do not confine my invention to its use, since there are other known forms of make-and-break switches which may be substituted for 90 the switch 53 and used to complete or break the circuit through the lamp and batteries.

At the back of the block 35 and preferably seated in part within the groove 42, is a vertical strip 57, shown in Figs. 3, 4 95 and 6, whose upper and lower ends are bent rearwardly and secured to the top and bottom sections 23, 24 of the casing. The strip 57 by closing the outer vertical side of the groove 42 excludes dust and dirt 100 which might find its way into the interior of the block 35 and in addition serves to tie the top and bottom sections 23, 24 of the casing together, thereby stiffening the casing and preventing said sections from 105 spreading outwardly from each other. When the strip 57 is made use of, reasonably thin material may be employed for the top and bottom sections of the main casing. I preferably form the upper and lower 110 ends of the strip 57 with hooks or flanges which extend toward each other and serve, when desired, to receive a sheet of fiber or other suitable material 58, as I illustrate in Fig. 6 and also in Fig. 3, and which sheet 115 of fiber will coöperate with the flaps 26, 27 in binding the battery cells in very firm position. The flexing of the spring conductors 49, 50 aids in binding the battery 120 cells vertically, and when the construction 125 as a whole has been completed we have a very compact and efficient portable electric light.

In Figs. 1 to 8 inclusive I illustrate the cells 36, 37 as reversed end for end, the 125 positive pole of the cell 36 being uppermost and the positive pole of the cell 37 extended downwardly, and this is a construction that I prefer, but to which I do not desire to be limited, because the cells may be arranged 130

with both positive poles extended upwardly or both positive poles extended downwardly, and in order that this feature of the construction may be understood I illustrate in Fig. 9 a modified arrangement of the conductor features which permit the positive poles of both battery cells to be extended downwardly. The casing 20 and exterior covering therefor employed in the construction shown in Fig. 9 are identical with the like features hereinbefore described in connection with the construction shown in Figs. 1 to 7 inclusive and therefore the details as to these features will not be specifically entered into. In Fig. 9 the battery cells 60, 61 correspond with the battery cells 36, 37 hereinbefore referred to, but are turned so that their positive poles extend downwardly, as shown in Fig. 9, and in the construction shown in Fig. 9 I employ a wooden block 62 carrying a threaded sleeve 64, lens ring 65, lens 66 and electric lamp and reflector, all as illustrated in Fig. 8, and therefore not requiring specific description. The construction shown in Fig. 9 is a modification in respect to the conductors for completing the circuit, and otherwise said construction corresponds with the structure shown in Figs. 1 to 7 inclusive. At the back of the block 62 is a vertical conductor strip 67 which has an inwardly bent portion corresponding with that numbered 44 in Fig. 8 which enters the block and serves as a contact for the end terminal of the lamp, and the said strip 67 has a lower extension 68 which extends below the block 62 and is secured by a rivet or the like 69 at its outer end in position to be engaged by the positive pole of the battery 61. The block 62 has secured to its back an additional conducting strip 70 which extends the full height of the block and has a laterally extending upper end section 71 secured on the top of the block 62, and at its lower end said strip 70 has a laterally extending portion 72 which extends below the block 62 and then toward the left, looking at Fig. 9, below the positive pole of the battery 60, the outer end of said conducting extension or section 72 being secured to the bottom of the casing by means of a rivet 73 or other suitable means. Extending vertically along the block 62 is a further conducting strip 74 having its upper end 75 in electrical connection with the threaded ring on the base thereof 65 and its other portion extended downwardly, as at 76, along the side of and engaging the zinc of the battery cell 60. Above the cell 60 I provide a spring 77 which serves to maintain said cell in firm position in engagement with the conductor 72; and above the cell 61 I provide a similar spring 78 which pressing against the negative pole of the battery 61 maintains the positive pole thereof in electrical

connection with the conductor 68. The spring 78 is, also, by means of an eyelet 79, placed in electrical connection with the housing 80, which contains the switch slide 81, and said slide 81 is adapted to be moved into engagement with an eyelet 82 concealed within the housing 80 whenever it is desired to complete the circuit and light the lamp. The eyelet 82 is in electrical connection with a spring 83 which presses upon the conductor 71 and thus is in electrical connection through the strip 70 and section 72 extending therefrom with the positive pole of the battery 60. The lamp is in connection, through the strip 67 and extension 68, with the positive pole of the battery 61, and as aforesaid the negative pole of the battery 61 is in electrical connection with the housing 80 and switch 81. The strip 67 extends from one terminal of the lamp, and the strip 74 represented by the parts 75, 76 is in electrical connection with the other terminal of the lamp and also with the zinc of the battery 60. The circuit is made or broken at the switch 81 in a manner which will be well understood from the description already presented. The construction shown in Fig. 9 embodies a rearrangement of the circuit conductors permitting the cells 60, 61 to be employed in what may be said to be inverted position or with the positive poles extended downwardly and the circuit is indicated diagrammatically in Fig. 17.

In Fig. 10 I illustrate another modification of my flash light, and in this modification the changes from the construction shown in the previously described figures of the drawings reside largely in the circuit connections permitting in this instance the positive holes of the two battery cells 90, 91 to extend upwardly. The exterior casing shown in Fig. 10 is substantially the same as the exterior casing shown in the other figures of the drawings, and Fig. 10 being a modification I number the wooden block placed therein as 92, and this block as in Figs. 7 and 9 carries the threaded sleeve 93 for the lens 94 and lens ring 95. The cells 90, 91 are mounted upon conducting springs 96, 97, respectively, and the conducting spring 96 is seated upon a conductor strip 98 which extends inwardly along the bottom of the casing and then upwardly as indicated by the dotted lines 99, and then inwardly, as at 100, to the metal sleeve or the base thereof 93, whereby the negative pole of the battery cell 90 becomes placed in electrical connection with the side terminal of the lamp. The spring 97 is seated upon a conductor strip 101 which extends inwardly below the block 92 and then upwardly, as indicated by the dotted lines 102 along the side of the groove in the back of the block 92, said groove corresponding with the groove 42; shown in

Fig. 5. The upper end of the vertical member of the conducting strip 101 is bent laterally, as at 103, and secured to the top of the block 92. The positive pole of the battery cell 90 is electrically connected by a strip 104 with the upper laterally bent end 103 of the conductor 101, said strip 104 being secured by rivets 105 and 106 to the lower surface of the top of the exterior main casing 20. The positive pole of the battery cell 91 is in electrical connection through a rivet or eyelet 107 with the switch housing 108, said rivet or eyelet 107 being utilized to secure one end of said housing on the top of the casing 20. The inner terminal of the lamp is in electrical connection with a vertical strip 109 which extends upwardly through the groove at the back of the block 92 and is bent over, as at 110, on the top of said block and secured thereto. A concealed eyelet 111 engages the upper end of the strip 109 and is exposed within the housing 108 and within said housing is the switch slide 112 which may be moved into engagement 25 with the rivet or eyelet 111 and thereby complete the circuit through the lamp and battery cells. Fig. 18 illustrates diagrammatically the circuits for the construction shown in Fig. 10, and since Fig. 10 only illustrates 30 a modified arrangement of the conducting strips for the circuit, I do not deem it necessary to enter into further detailed description concerning the same.

In Figs. 11, 12 and 13 I illustrate a further modification of the invention wherein the interior shell may be of metal, if desired, instead of non-conducting material, and in this instance the battery cells 113 and 114 should be covered with non-conducting material 40 115. The casing shown in Figs. 11, 12 and 13 contains the wooden block 116 carrying the metallic sleeve 117, reflector 118, lens 119 and lens-ring 120, all as described with respect to the block shown in Figs. 3 to 7 inclusive, and in the back of the block 116 there is a vertical conducting strip 121 which is bent inwardly, as shown in Figs. 12 and 13, to form a spring contact for the end terminal of the lamp, the other terminal of 50 the lamp being in electrical engagement with the reflector. In the construction shown in Figs. 11, 12 and 13, the negative pole of the battery 113 rests upon a conducting strip 122 which extends inwardly and is 55 connected with the vertical conductor 121, thereby placing the negative pole of the battery 113 in electrical connection with the end terminal of the lamp. The negative pole of the battery 114 is in engagement with a conductor 123 whose inner end is in electrical connection with an eyelet or rivet 124 concealed within the housing 125. The positive pole of the battery 113 is in electrical connection with a conductor 126, which is secured to the housing 125 by an eyelet or rivet 60 65

127, and said positive pole of the battery 113 is therefore in electrical connection with the housing 125 and switch 128 therein. The positive pole of the battery 114 is seated on a contact spring 129 which extends inwardly below the block 116 and then vertically, as at 130, into electrical connection with the threaded sleeve 117 carried by said block. When the switch slide 128 is moved into engagement with the eyelet 124 of the conductor 123 it establishes the circuit through the lamp and the lamp will become lighted, and when said switch slide 128 is moved from engagement with the eyelet 124, the circuit will be broken and the light will be extinguished. Fig. 16 illustrates diagrammatically the circuits for the construction shown in Figs. 11, 12 and 13, and since the construction shown in Figs. 11, 12 and 13 only differs from the construction shown in Figs. 1 to 8 inclusive in details of the casing construction, it is thought that only brief further detailed explanation of the construction shown in Figs. 11, 12 and 13 will be required. It is to be understood, however, that the cells 113 and 114 are insulated from the general casing, said casing being of metal, and that the upper and lower ends on top and bottom of the casing must either be of insulating material or contain fiber linings. 95

In the construction shown in the drawings, the flat back and front and rounded ends of a casing part 131 are formed in one piece, and a metallic bottom 132 is also formed in one piece with the casing part 100 131. The bottom 132 is provided with an insulating lining 133, and the upper end 134 of the casing is formed of insulating material and is arranged to be opened by means of a hinge 135 appearing in Fig. 12. Obviously the casing may be provided with an outer covering of leather or other suitable material if desired. 105

In all of the forms of the invention illustrated there will be provided all of the conveniences hereinbefore described with respect to Figs. 1 to 8 inclusive, and it has not been deemed necessary to illustrate the exterior covering or wrapping, loops and other features in common for the constructions 110 shown in Figs. 9 to 13 inclusive, since they will be the same as for the constructions presented in Figs. 1 to 5 inclusive. In each of the constructions shown is presented the oval casing containing the wooden block 120 parallel battery cells and other features common to the construction shown in Figs. 3 to 7 inclusive. I present Figs. 9 to 13 inclusive so as to indicate that my invention is not limited to all of the details of arrangements of conductors and other parts specifically described with respect to Figs. 1 to 8 inclusive. 115 120 125

My invention is not therefore limited to details of arrangement for the circuits, nor 130

to other details of form or construction otherwise than the appended claims may require.

What I claim as my invention and desire 5 to secure by Letters-Patent, is:

1. A portable electric light comprising a casing having a front opening and a back capable of being opened and closed, a non-conducting block within said casing disposed between the top and bottom thereof and intermediate the ends of the casing and with said ends forming parallel chambers for battery-cells, a sleeve secured to the front of said block and positioned with respect to the front opening in the casing, a reflector and lamp entered within said sleeve, a lens and lens-ring applied to said sleeve and exposed at the front opening in the casing, battery-cells in the aforesaid parallel chambers, a manually operative switch on said casing, and conductors for the circuit through the lamp and batteries to the switch terminals to be connected by the switch.

25 2. A portable electric light comprising a casing having a front opening, a back formed of overlapping flexible flaps equipped with means whereby they may be secured together at their free ends and means for suspending the light, a non-conducting block within said casing disposed between the top and bottom thereof and intermediate the ends of the casing and with said ends forming parallel chambers for battery-cells, a sleeve secured to the front of said block and positioned with respect to the front opening in the casing, a reflector and lamp entered within said sleeve, a lens and lens-ring applied to said sleeve and exposed at the front opening in the casing, battery-cells in the aforesaid parallel chambers, a manually operative switch on said casing, and conductors for the circuit through the lamp and batteries to the switch terminals to be connected by the switch.

30 3. A portable electric light comprising a casing having a front opening, rounded ends conforming to the side of battery-cells, a back formed of overlapping flexible flaps equipped with means whereby they may be secured together at their free ends, a non-conducting block within said casing disposed between the top and bottom thereof and intermediate the ends of the casing and with said ends forming parallel chambers for battery-cells, a sleeve secured to the front of said block and positioned with respect to the front opening in the casing, a reflector and lamp entered within said sleeve, a lens and lens-ring applied to said sleeve and exposed at the front opening in the casing, battery-cells in the aforesaid parallel chambers, a manually operative switch on said casing, and conductors for the circuit through the lamp and batteries to the switch terminals

to the switch terminals to be connected by the switch.

4. A portable electric light comprising a casing having a front opening, rounded ends conforming to the side of battery-cells, 70 a back formed of overlapping flexible flaps equipped with means whereby they may be secured together at their free ends and also with loops whereby the light may be suspended, a non-conducting block within said 75 casing disposed between the top and bottom thereof and intermediate the ends of the casing and with said ends forming parallel chambers for battery-cells, a sleeve secured to the front of said block and positioned 80 with respect to the front opening in the casing, a reflector and lamp entered within said sleeve, a lens and lens-ring applied to said sleeve and exposed at the front opening in the casing, battery-cells in the aforesaid 85 parallel chambers, a manually operative switch on said casing, and conductors for the circuit through the lamp and batteries to the switch terminals to be connected by the switch.

5. A portable electric light comprising a casing having a front opening, a back capable of being opened and closed and a flexible handle-loop fastened at its ends and adapted to be folded on itself, and then down 95 against said casing and being equipped with snap-fastener members for securing it in its folded-down position, a non-conducting block within said casing disposed between the top and bottom thereof and intermediate 100 the ends of the casing and with said ends forming parallel chambers for battery-cells, a sleeve secured to the front of said block and positioned with respect to the front opening in the casing, a reflector and lamp entered within said sleeve, a lens and lens-ring applied to said sleeve and exposed at the front opening in the casing, battery-cells in the aforesaid parallel chambers, a manually 105 operative switch on said casing, and conductors for the circuit through the lamp and batteries to the switch terminals to be connected by the switch.

6. A portable electric light comprising a casing having a front opening and a back capable of being opened and closed, a non-conducting block within said casing disposed between the top and bottom thereof and intermediate the ends of the casing and with 110 said ends forming parallel chambers for battery cells, a sleeve secured to the front of said block and positioned with respect to the front opening in the casing, a reflector and lamp entered within said sleeve, a lens and lens-ring applied to said sleeve and exposed at the front opening in the casing, battery-cells in the aforesaid parallel chambers, a manually 115 operative switch on said casing, and conductors for the circuit through the lamp and batteries to the switch terminals

to be connected by the switch, those portions of said conductors more directly connected with the two terminals of the lamp being secured to, and permanently carried by said block.

7. A portable electric light comprising a casing having a front opening and a back capable of being opened and closed, a non-conducting block within said casing disposed between the top and bottom thereof and intermediate the ends of the casing and with said ends forming parallel chambers for battery-cells, a sleeve secured to the front of said block and positioned with respect to the front opening in the casing, a reflector and lamp entered within said sleeve, a lens and lens-ring applied to said sleeve and exposed at the front opening in the casing, battery-cells in the aforesaid parallel chambers, a manually operative switch on said casing, and conductors for the circuit through the lamp and batteries to the switch terminals to be connected by the switch, one portion of said conductors being carried by said block and connected with said sleeve which is in electrical connection with one terminal of the lamp, and another portion of said conductors being extended along the back of the block and having an offset section extended in an opening in the block to afford a contact for the end terminal of the lamp.

8. A portable electric light comprising a casing having a front opening and a back 35 capable of being opened and closed, a non-conducting block within said casing disposed between the top and bottom thereof and intermediate the ends of the casing and with said ends forming parallel chambers 40 for battery-cells, a sleeve secured to the front of said block and positioned with respect to the front opening in the casing, a reflector and lamp entered within said sleeve, a lens and lens-ring applied to said sleeve 45 and exposed at the front opening in the casing, battery-cells in the aforesaid parallel chambers, a manually operative switch on said casing, and conductors for the circuit through the lamp and batteries to the switch 50 terminals to be connected by the switch, said conductors comprising strips carried by said block and leading, respectively, from the lamp terminals to the positive pole of one battery and the negative pole of the other 55 battery, and strips respectively engaging the other poles of said batteries and to be electrically connected by said switch to complete the circuit.

9. A portable electric light, comprising a
casing having a front opening, a non-con-
ducting block within said casing disposed
between the top and bottom thereof and in-
termediate the ends of the casing, a sleeve at
the front of said block positioned with re-
spect to the front opening in the casing, a

reflector and lamp entered within said sleeve, a lens and lens ring applied to said sleeve and exposed at said front opening, battery cells within the ends of said casing, a manually operative switch on said casing and conductors for the circuit through the lamp and batteries to the switch terminals to be connected by the switch, one portion of said conductors being carried by said block and connected with said sleeve which is in electrical connection with one terminal of the lamp, and another portion of said conductors being extended along the back of the block and affording a contact for the end terminal of the lamp. 70 75 80

10. A portable electric light comprising a casing having a front opening, a non-conducting block within said casing disposed between the top and bottom thereof and intermediate the ends of the casing, a sleeve 85 at the front of said block and positioned with respect to the said front opening, a reflector and lamp entered within said sleeve, a lens and lens ring applied to said sleeve and exposed at said front opening, battery 90 cells within the ends of said casing, a manually operative switch on said casing and conductors for the circuit through the lamp and batteries to the switch terminals to be connected by the switch, those portions of said 95 conductors more directly connected with the two terminals of the lamp being secured to and permanently carried by said block.

11. A portable electric light comprising a casing having a front opening, a non-conducting block within said casing disposed between the top and bottom thereof and intermediate the ends of the casing, a tie-bar secured to said top and bottom at the back of said block, a sleeve at the front of said block and positioned with respect to the said front opening, a reflector and lamp entered within said sleeve, a lens and lens ring applied to said sleeve and exposed at said front opening, battery cells within the ends of said casing, a manually operative switch on said casing and conductors for the circuit through the lamp and batteries to the switch terminals to be connected by the switch, those portions of said conductors more directly connected with the two terminals of the lamp being secured to and permanently carried by said block. 100 105 110 115

12. A portable electric light comprising a casing having a front opening, a non-conducting block in said casing disposed between the top and bottom thereof and intermediate the ends of the casing, a tie-bar secured to said top and bottom at the back of said block and having flanged ends extending toward each other, a backing sheet detachably held by the flanges of said bar, a sleeve at the front of said block and positioned with respect to the said front opening, a reflector and lamp entered within said 120 125 130

sleeve, a lens and lens ring applied to said sleeve and exposed at said front opening, battery cells within the ends of said casing, a manually operative switch on said casing 5 and conductors for the circuit through the lamp and batteries to the switch terminals to be connected by the switch, those portions of said conductors more directly connected with the two terminals of the lamp being secured to and permanently carried by said block.

13. A portable electric light comprising a casing having a front opening, a non-conducting block within said casing disposed 15 between the top and bottom thereof and intermediate the ends of the casing, a sleeve at the front of said block positioned with respect to the front opening in the casing, a reflector and lens entered within said sleeve, 20 a lens and lens ring applied to said sleeve and exposed at the said front opening, battery cells within the ends of said casing, a manually operative switch on said casing and conductors for the circuit through the 25 lamp and batteries to the switch terminals to be connected by the switch, said conductors comprising strips carried by said block and leading, respectively, from the lamp terminals to the positive pole of one battery and 30 the negative pole of the other battery, and strips respectively engaging the other poles of said batteries and to be electrically connected by said switch to complete the circuit.

14. A portable electric light comprising a 35 casing having a front opening, a block within said casing disposed between the top and bottom thereof and intermediate the ends of the casing and with said ends forming parallel chambers for battery cells, a sleeve at 40 the front of said block positioned with respect to the front opening in the casing, a reflector and lamp entered within said sleeve, a lens and lens ring applied to said sleeve and exposed at the said front opening, parallel 45 battery cells within said chambers, a manually operative switch on said casing, and conductors for the circuit through the lamp and batteries to the switch terminals to be connected by the switch.

15. A portable electric light comprising a 50 casing having a front opening, a block within said casing disposed between the top and bottom thereof and intermediate the ends of the casing and with said ends forming parallel chambers for battery cells, a sleeve at 55 the front of said block positioned with respect to the front opening in the casing, a reflector and lamp entered within said sleeve, a lens and lens ring applied to 60 said sleeve and exposed at the said front opening, parallel battery cells within said chambers, a manually operative switch on said casing, and conductors for the circuit

through the lamp and batteries to the switch terminals to be connected by the switch, 65 said conductors comprising strips carried by said block and leading respectively from the lamp terminals to the positive pole of one battery and the negative pole of the other battery, and strips respectively engaging the other poles of said batteries and to be electrically connected by said switch to complete the circuit.

16. In a portable electric lamp, the combination of spaced battery cells, a spacing 75 block separating said cells, said block having a tapered chamber for receiving an electric bulb and reflector, said block also having a groove therein, and a passage extending through said block connecting said chamber with said groove, a conductor strip in said groove and passage in contact with said bulb, and a casing inclosing said cells and block.

17. A cell spacing block for a portable 85 electric lamp, said block having an electric bulb receiving chamber on one face, and a groove on the opposite face thereof, said chamber and groove being connected by a passage through said block, and a conductor in said groove and passage.

18. A cell spacing member for a portable electric lamp, said spacing member having a recess for an electric bulb, and a sleeve secured to said member surrounding said 95 recess.

19. A portable electric lamp comprising spaced cells, a casing embracing the cells, said casing having a central opening, an intermediate block for spacing said cells and for carrying an electric bulb, and a sleeve secured to said block and projecting through the opening in the casing.

20. A portable electric lamp comprising a casing embracing spaced cells, said casing having a central opening, a spacing block in said casing separating said cells, said block having a recess for a bulb and a reflector, a sleeve carried by said block around said recess, said sleeve projecting through the opening in the casing, a lens, and a lens ring secured to said sleeve.

21. A portable electric lamp comprising spaced cells, a recessed member between said cells for spacing them apart, a lamp, a reflector, and means mounted on said recessed member for supporting said lamp and said reflector thereon with portions thereof projecting into such recess.

Signed at New York, in the county of 120 New York, and State of New York, this 24th day of April, A. D. 1918.

DAVID L. GRAFF.
